UNITED STATES PATENT OFFICE

EDWIN V. WHITAKER, OF GLOVERSVILLE, NEW YORK.

ROLLER-SKATE.

SPECIFICATION forming part of Letters Patent No. 330,652, dated November 17, 1885.

Application filed September 12, 1885. Serial No. 176,937. (Model.)

To all whom it may concern:

Be it known that I, EDWIN V. WHITAKER, a citizen of the United States, and a resident of Gloversville, in the county of Fulton and State 5 of New York, have invented certain new and useful Improvements in Roller-Skates; and I do hereby declare that the following is a full, clear, and exact description of the invention, which will enable others skilled in the art to 10 to which it appertains to make and use the same, reference being had to the accompanying drawings, which form a part of this specification, and in which—

Figure 1 is a perspective view of my improved roller-skate, and Fig. 2 is a longitudinal vertical sectional view of the same.

Similar letters of reference indicate corresponding parts in both the figures.

My invention has relation to that class of 20 roller-skates in which the frames for the rollers are pivoted to turn in a horizontal plane, and provided with reaches pivotally connected to each other, and which have a straight spring secured to the under sides of the roller-bearing frames and to the reaches at their points 25 of union; and it consists in the improved construction and combination of parts of the same.

In the accompanying drawings, the letter A indicates the foot-board, which is provided 30 with the usual toe-clamps, B, and heel-clamps C, which may be of any desired construction, or with any other suitable form of fastening. This foot-board, which may be made in one, as shown in the drawings, or in two parts—35 one heel portion and one toe portion—is provided at the heel portion with two downwardly-bent lips, D and E, having perforations F, through which the screw G, which operates the heel-clamp, passes, and the toe 40 or sole portion of the foot-board is formed with two downwardly-bent lips, H and I, through perforations J, in which lips a longitudinal screw, K, passes. A longitudinal bar, L, has perforated upwardly-projecting 45 lips or lugs M, which bear against the inner sides of the downwardly-projecting lips of the foot-board, and the longitudinal screws pass through the perforations in the said lips and rock in the same, allowing the foot-board to 50 rock upon the longitudinal bar. The longitudinal bar is provided at its ends with downwardly-projecting cylindrical lugs N, having

an axial perforation, O, and an annular groove, P, in the lower end, and these lugs fit into cylindrical sockets Q, projecting upward from the roller-bearing frames R. The sockets have annular grooves S in their bottoms, and have axial perforations T, and anti-friction balls U are placed in the annular grooves of the sockets and fit into the annular grooves of the cylindrical lugs, forming an anti-frictional support for the same. If desired, annular washers may be interposed between the downwardly-projecting lugs and the sockets, into which they are inserted, as shown at w, to 60 compensate for wear against the inner sides of the cylindrical sockets. A bolt, V, having a flat perforated head, W, which fits into a recess, X, in the roller-bearing frame, passes up through the axial perforations of the socket 65 and lug, and has a screw-threaded perforation, Y, in its upper end, into which passes the end of a screw, Z, the head of which bears against the upperside of the longitudinal bar, this screw securing the lug into the socket and the entire 70 roller-bearing frame to the end of the longitudinal bar. The perforation through which the axle A' of the rollers B' passes registers with the perforation in the head of the bolt V, so that the said axle will hold the bolt in position. 75 The roller-bearing frames have inwardly-projecting screw-threaded sockets C', into which fit the screw-threaded ends of the reaches D' and E', which are respectively formed with a flat head having a perforation, F', and with 80 two longitudinally-slotted lips, G', between which the flat head fits and is retained by a bolt, H', which passes up through the slotted lips and the perforation in the head, and which is provided with a transversely-perforated 85 head, I', and with a transverse perforation, J', in its upper end for the insertion of a pin or split key, K'. The heel-piece is provided with a downwardly-projecting socket, L', which passes through a transverse aperture, 90 M, in the longitudinal bar, and the upwardly-projecting end of a bolt, N', fits into this socket, while its lower end is formed with an eye, O', which fits upon the inwardly-projecting socket portion of the rear roller-bearing frame. The flat perforated heads of the bolts connecting the cylindrical lugs and the 95 sockets of the roller-bearing frames are formed with downwardly-projecting lugs P', having

longitudinal perforations Q', and a rod, R', of spring-wire passes through these perforations and through the perforated head of the bolt which unites the reaches.

- 5 It will now be seen that when the foot-board is tilted to one side or the other the telescoping post projecting from the heel-piece down to the rear reach will turn the rear roller-bearing frame to the side, which again, by reason 10 of the pivotally-united reaches, will turn the other frame, so that the rollers, while being in a horizontal plane at the same time will stand at angles to each other, guiding the skate in a curved direction, and the spring at 15 the under sides of the roller-bearing frames and passing through the pivotal bolt will offer sufficient resistance to prevent the foot-board to tilt too far down to a side or the frames and rollers from turning too far.
- 20 The foot-board may, as before stated, be divided into a sole portion and a heel portion, in which case each portion will have its separate telescoping post extending down to the reach, and where the foot-board is made in 25 one piece the telescoping post may be equally as well extended from the sole portion as from the heel portion.

The anti-friction balls between the sockets and cylindrical lugs may be dispensed with 30 where cheapness is more desirable than reduction of resistance, and either washers interposed between the lugs and sockets; or their meeting surfaces may bear directly against each other with nothing interposed.

35 By extending the reaches in their sockets they will be enabled to be turned farther out to the sides, thus increasing the yielding properties of the skate, while naturally the contracting of the reaches will accomplish the 40 opposite effect.

The spring rod or bar is retained in its perforations by means of a small set-screw, S', passing into the perforation in the head of the pivotal bolt for the reaches, bearing with its 45 end against the spring.

By having the telescopic post projected from the heel portion of the foot-board the weight of the body thrown upon the side of the foot when turning or describing a curve 50 will be thrown upon the rear rollers exclusively, and will in this manner not stop the speed, as when the weight of the body is thrown upon the toe, which will stop the speed considerably.

55 Having thus described my invention, I claim and desire to secure by Letters Patent of the United States—

1. In a roller-skate, the combination of a longitudinal bar, roller-bearing frames pivoted to turn horizontally upon the under sides of the ends of the same, and having inwardly-projecting reaches pivotally and extensibly connected to each other, and a foot-board having a post projecting downward and movably attached to one of the reaches, as and for 55 the purpose shown and set forth.

2. In a roller-skate, the combination of a

longitudinal bar having downwardly-projecting cylindrical lugs at its ends, roller-bearing frames having cylindrical sockets receiving the lugs, bolts passing axially through the cylindrical lugs and sockets, reaches projecting inwardly from the roller-bearing frames and having their ends pivotally and extensibly connected, a spring-bar attached to the 70 roller-bearing frames and to the uniting-bolt for the reaches, and a foot-board rocking upon the longitudinal bar and having a downwardly-projecting telescoping post movably attached at its lower end to one of the reaches, 75 as and for the purpose shown and set forth.

3. In a roller-skate, the combination of a longitudinal bar having the rocking foot-board attached to its upper side, and having two downwardly-projecting cylindrical lugs 80 at its ends formed with axial perforations and with annular grooves in their lower ends, with roller-bearing frames connected by pivotally and extensibly united reaches, and provided with sockets for the lugs having axial perforations, and annular grooves in their bottoms, 85 anti-friction balls placed in the grooves, and bolts passing up through the axial perforations and secured to the longitudinal bar, as and for the purpose shown and set forth. 95

4. In a roller-skate, the combination of the roller-bearing frames pivoted to swing horizontally, and having the inwardly-projecting threaded sockets and the downwardly-projecting perforated lugs, the reach having the 100 perforated flat head and fitting in the socket of one roller-frame, the reach having the longitudinally-slotted lips and fitting in the other socket, the bolt passing through the slots and the perforated head, and having a transversely-perforated head provided with a set-screw, and the spring-rod passing through the perforated lugs and through the perforated head of the bolt, being retained by the bolt, as and for the purpose shown and set forth. 105

5. In a roller-skate, the combination of a longitudinal bar having downwardly-projecting cylindrical lugs at its ends, roller-bearing frames having cylindrical lugs projecting upward, washers interposed between the said lugs, bolts passing axially through the cylindrical lugs, reaches projecting inwardly from the roller-bearing frames and having their ends pivotally and extensibly connected, a spring-bar attached to the roller-bearing frames and to the uniting-bolt for the reaches, and a foot-board rocking upon the longitudinal bar and having a downwardly-projecting telescoping post movably attached at its lower end to one 115 of the reaches, as and for the purpose shown and set forth. 120

In testimony that I claim the foregoing as my own I have hereunto affixed my signature in presence of two witnesses.

EDWIN V. WHITAKER.
